INVENTOR

Albion M. Goldstein.

By Joseph Koenig
ATTORNEY

UNITED STATES PATENT OFFICE.

ALBION M. GOLDSTEIN, OF ST. LOUIS, MISSOURI.

COMBINED COLLAR BUTTON AND NECKTIE-GUIDING DEVICE.

Application filed December 11, 1922. Serial No. 606,165.

To all whom it may concern:

Be it known that I, ALBION M. GOLDSTEIN, a citizen of the United States, residing in the city of St. Louis, State of Missouri, have

5 invented a certain new and useful Improvement in Combined Collar Buttons and Necktie-Guiding Devices, of which the following is a specification, reference being had to the accompanying drawing, forming 10 a part thereof.

This invention relates to a certain new and useful improvement in combined collar-buttons and necktie guiding-devices and has for its principal object the provision of a 15 relatively simple, inexpensive device which may be easily removably attached to and upon the collar and which in use is adapted efficiently for detachably securing the collar to the neckband of a shirt and at the 20 same time supporting and guiding the necktie at the back of the collar so as to eliminate any tendency of the tie to bind while being pulled lengthwise through the collar when the necktie is being adjusted.

25 With the above and other objects in view, my present invention resides in the novel features of form, construction, arrangement, and combination of parts hereinafter described and afterwards pointed out in the 30 claims.

In the accompanying drawing,

Figure 1 is an elevational view of a standard form of collar equipped with a combined collar-button and necktie guiding-device embodying my invention;

Figure 2 is a fragmental perspective view, taken as on the line 2—2, Figure 1, showing the device as in use in connection with a shirt and collar; and

40 Figure 3 is a perspective view of a combined collar-button and necktie guiding-device of my invention.

Referring now more in detail and by reference characters to the said drawing, 45 which illustrates a preferred embodiment of my invention, the device as a whole is constructed from a single piece of suitable bendable sheet metal of suitable length and preferably of uniform width throughout its 50 length, and the metal having also a certain amount of resiliency.

In the construction or development of the device, the strip is bent at a point intermediate its ends to form a flattened loop 1, 55 which performs the function of the head of the collar-button, and extending at right

angles from the center portion of the loop or head 1, are horizontally disposed closely adjacent parallel portions 2, which constitute or form the shank of the button or that portion of the device which passes through the button-hole of the collar-band of the shirt.

From the rear end of the lower shank-member 2, the strip of metal is first laterally 65 extended downwardly a relatively short distance, as at 3, then bent to extend upwardly a relatively greater distance, as at 4, and then again bent to extend downwardly, as at 5, thereby forming a so-called inverted 70 substantially U-shaped loop 6 open at its upper end and having its bight presented upwardly and a second oppositely disposed substantially U-shaped loop 7 open at its lower end and having its bight presented 75 downwardly. The leg-portion 4 is thus common to both the loops 6 and 7, the former of which is what I designate as the collar-engaging loop of the device, the legs 80 3 and 4 of loop 6 being disposed more or less closely together in yielding relation. The latter loop 7 is adapted to fit in the fold of the collar and to receive and serve as a slip-guide for the tie when the latter is also positioned within the collar-fold.

85 From the rear end of upper shank-member 2, the end portion of the strip is laterally extended upwardly, as at 8, to form substantially a button-hole engaging prolongation of leg-portion 3 of the loop 6.

90 It will be understood that my present device is particularly designed for use in connection with the now generally worn so-called turn-over collars, and when the device is applied for use, the device is removably 95 engaged at its loop 6 with the inner band-portion 9 of the collar, as best seen in Figure 2, and leg-extension 8 inserted endwise through the button-hole of the collar to project within the collar-fold 10. As so disposed upon the collar, the device as a whole is frictionally held from removal by means of the gripping-engagement between the yielding legs 3 and 4 of loop 6 and the collar-band 9, the extension or tongue 8 in its 100 engagement with the button-hole of the collar retaining the device in proper upright position and preventing sidewise tilting or shifting thereof. As so attached and positioned upon the collar, the head 1 is presented inwardly for convenient engagement 105 as is usual with the collar-band of a shirt,

and the loop 7 is disposed in the fold 10 of the collar, as clearly illustrated in Figure 2, and provides a firm and substantial support for that portion of the tie that passes in the rear portion of the fold of the collar. The tie can thus be readily pulled or slipped lengthwise in the fold of the collar without any tendency to roll or twist.

A combined collar-button and necktie guiding-device of my invention is comparatively simple in form and construction, may be easily and cheaply produced, and is very efficient and effective in performing its intended functions. It will be understood, of course, that various modifications in the size, form, and construction of the several parts of the device may be resorted to without departing from the nature and spirit of my invention.

Having thus described my invention, what I claim and desire to secure by Letters Patent is:

1. A combined collar-button and necktie guiding-device including a shirt-engaging head, a shank, an attaching-loop for frictionally gripping the collar, and a second loop for slip-guiding a tie in the fold of the collar.

2. A combined collar-button and necktie guiding-device including a shirt-engaging head, a shank, an attaching loop for frictionally engaging the collar, and a second loop for slip-guiding a tie in the fold of the collar, said loops having a common leg-member and being oppositely disposed the one to the other.

3. A combined collar-button and necktie guiding-device including a shirt-engaging head, a shank, an attaching loop for engag-

ing the collar, and a second loop for slip-guiding a tie in the fold of the collar, said loops having a common leg-member and being oppositely disposed the one to the other and the legs of the attaching loop being relatively yielding for frictionally gripping the collar.

4. A combined collar-button and necktie guiding-device including a shirt-engaging head, a shank, an attaching loop for engaging the collar, a second loop for slip-guiding a tie in the fold of the collar, said loops having a common leg-member and being oppositely disposed the one to the other and the legs of the attaching loop being relatively yielding for frictionally gripping the collar, and a lateral extension upon the shank for engagement with the button-hole of the collar for preventing sidewise shifting of the device.

5. A combined collar-button and necktie-guiding device constructed from a single strip of metal bent to include a shirt-engaging head, a shank extending laterally from the head, a U-shaped attaching loop having its bight presented upwardly relatively to the shank, a U-shaped tie-guiding loop having its bight presented downwardly relatively to the shank, said loops having a common leg-member and the legs of the attaching loop being relatively yielding for frictionally gripping the collar, and a lateral extension upon the shank for engagement with the button hole of the collar for preventing side-wise shifting of the device.

In testimony whereof, I have signed my name to this specification.

ALBION M. GOLDSTEIN.
